Figure 1. is a front elevation, and

Figure 2. is a side elevation of the stove.

Similar characters of reference in the several figures denote the same part of stove and design. Where the ornament is symmetrical, but one half of the detail is shown. —

Each of the front doors A. .... bears on its panel, an ornament in bas-relief, composed of cross figure a, lozenge projection b, scrolls c. and foliage d. arranged and having the configuration set forth in figure 1. The upper doors B. are ornamented in bas-relief with sweeps scrolls, and foliage, arranged and configured as set forth in the above named figure. On the band C. between the doors A. and B. is the inscription "Emporium" in raised capitals. —

The side plate D. bears three panels E. F. G. two forming the oven doors, and the other cast with the plate. The panels E. F. each bear an ornament in bas-relief composed of foliage, sweeps scrolls, and cross figures f. arranged and configured as shown in figure 2. The bas-relief ornament on the panel G. is made up of the same elements as the ornaments on E. and F. but varying in dimensions, as set forth in the above named figure.
